ATTORNEY

UNITED STATES PATENT OFFICE.

MAX W. KAUFMANN, OF NEW YORK, N. Y., ASSIGNOR TO L. W. LEVY & CO.,
OF SAME PLACE.

DESIGN FOR AN EYEGLASS-GUARD.

SPECIFICATION forming part of Design No. 31,883, dated November 28, 1899.

Application filed August 3, 1899. Serial No. 726,054. Term of patent 14 years.

To all whom it may concern:

Be it known that I, MAX W. KAUFMANN, a citizen of the United States, and a resident of New York, in the county of New York and State of New York, have invented and produced a new and original Design for Eyeglass Guards, of which the following is a specification.

In the accompanying drawings, to which reference is made and which form a part of this specification, Figure 1 is a plan view showing my newly-designed eyeglass-guard. Fig. 2 is an edge view of the same, and Fig. 3 is a cross-section.

The leading feature of my design consists of a straight or vertical member *a* and two

opposite diagonal members or arms *b c*, which join the edge of the member *a* at or about the center of its length, so that the members *b c* together form an angle *d*, the members *a b* ²⁰ and *a c* forming an angle *e*, and the members *a c* forming an angle *f*, the apexes of said angles being grouped together at the center of the guard.

Having thus described my invention, what I claim as new, and desire to secure by Letters ²⁵ Patent, is—

The design for an eyeglass-guard, as herein shown and described.

MAX W. KAUFMANN.
